UNITED STATES PATENT OFFICE.

MATTHEW CARR, OF BERWYN, ILLINOIS, ASSIGNOR TO JOSEPH C. CARRY, OF CHICAGO, ILLINOIS.

REFRIGERATOR CAR.

Application filed August 19, 1926. Serial No. 130,300.

This invention relates to refrigerator railway cars, and more particularly to the hatchways and plugs therefor.

One of the objects of the invention is the provision of new and improved means for rendering the joint between the plug and walls of the hatchway airtight.

Another object of the invention is the provision of new and improved means at the corners of the hatchway whereby the plug may be easily inserted with a minimum amount of friction and an airtight joint be formed.

A still further object of the invention is the provision of new and improved lining for the corners of a hatchway that is cheap to manufacture, easily applied to the hatchway, and when applied is efficient in use and durable and rugged in construction.

Other and further objects and advantages of the invention will appear from the following description taken in connection with the accompanying drawings, in which—

Fig. 1 is a vertical section of the upper portion of a refrigerator car showing the invention in position therein;

Fig. 2 is a cross-section on line 2—2 of Fig. 1;

Fig. 3 is a section on line 3—3 of Fig. 1; and

Fig. 4 is a perspective view of a corner of a hatchway showing the invention in position thereon, with parts broken away.

In the construction of hatches or hatchways and plugs or closures therefor great difficulty has been experienced in so constructing the parts that the joint between the plug and the walls of the hatchway will be airtight. It is common practice to make the hatchways rectangular in cross-section and to pad the plugs or closures therefor on their peripheral or engaging surfaces in order to make an airtight joint between the plugs and hatchway walls, but it is extremely difficult if not impossible to so construct the corners of the plug that the padding thereon will make a close fit with the walls in the corners of the hatchway. In order to overcome this difficulty it has been proposed to employ a special corner attachment as by padding the corners of the hatchway, but this is impractical because the great amount of friction between the padding on the plug and the attachment on the corners of the hatchway in inserting and removing the

plug soon wears and destroys the attachment or the padding on the plug, or both.

The present invention seeks to remedy this defect and to so construct the parts that an airtight joint is formed, and at the same time friction between the parts is reduced to a minimum.

A form of the device illustrating one embodiment of the invention will now be described. Referring to the drawings, in which the same reference characters designate the same parts throughout the description, the numeral 10 designates a refrigerator car having the usual deck 11 and ceiling 12 beneath and spaced from the same. Since the specific features of the car constitute no part of the present invention, it is not thought necessary to further illustrate or describe the same.

The roof or deck of the car is provided with the usual hatch or hatchway 13 above the ice bunkers through which ice is delivered to the same. This passage is rectangular in cross-section and is tapered downwardly in the usual manner.

A plug 14 is provided for the hatchway. This plug may be of the usual construction and comprises a hollow wooden construction filled with suitable heat insulating material 14. The plug is tapered to correspond with the tapered hatchway and is provided on its edges with a padding of heat insulating material 15 which is held in position by a suitable fabric 16 secured to the plug whereby the latter may be wedged into the hatchway.

The walls of the hatchway are preferably though not necessarily lined with sheet metal 17 to facilitate the insertion and removal of the plug.

In order to form airtight joints at the corners of the hatchway, corner pieces 18, curved in cross-section, are provided. These corner pieces are formed from any suitable material such as sheet metal and as shown have top and bottom flanges 19 and 21 extending over and beneath the walls 22 forming a hatchway for securing said pieces in the corners thereof. These corner pieces are curved in cross-section as clearly shown in Fig. 3. The radius of the curve at the upper portion of each corner piece is short and gradually increases in length toward the lower portion thereof, whereby a substantially square corner is formed at the upper

portion of the corner piece as shown in Fig. 2, which gradually merges into a broad curve toward the intermediate portion of said piece, as clearly shown in Fig. 3. This 5 arrangement results in a tapering or converging of the corner pieces downwardly. The space between the corner pieces and the corner of the hatchway is closed at each end by the flanges 19 and 21, thus forming 10 a pocket of air which prevents the transmission of heat through this portion of the hatchway. The corner pieces 18 are shown as extending over the lining 17 but it is understood it may be otherwise. 15 If it is desired to form a cheaper construction the upper flange 19 may be dispensed with, since the structure is sufficiently rigid without it when the device is in position in the hatchway. In this event the 20 space between the corner pieces and the walls of the hatchway may be filled with insulating material, if desired, although this is hardly necessary since the space is so narrow and so long that there is little or 25 no circulation of air therein.

These corner pieces are secured to the corners of the hatchway by any suitable means as the nails or rivets 23 the heads of 30 which are flush with the surface of said corner pieces, as clearly shown in Fig. 2.

When the plug 14 is inserted in the hatchway the corners thereof will make a tight fit with the sides of the hatchway and the corner pieces thereof, thus forming an air-tight joint about the entire periphery of 35 said plug. Owing to the tapering of the plug and hatchway the plug may be forced into the passageway as tightly as may be desired. Due to the fact that the plug-en- 40 gaging surfaces of the hatchway are of metal a minimum resistance is offered to the introduction and removal of the plug.

A cover 24, of the usual or any well-known construction, is provided for the 45 hatchway, as shown in Fig. 1.

It is thought from the foregoing taken in connection with the accompanying drawings that the construction and operation of my device will be apparent to those skilled 50 in the art, and that various changes in size,

shape, proportion and details of construction may be made without departing from the spirit and scope of the appended claims.

I claim as my invention:

1. In a refrigerator car having a hatchway through the roof thereof, a lining for said hatchway, a padded plug for closing said hatchway, and a curved corner piece in each corner of said hatchway for forming with said pad an air-tight joint. 55

2. In a refrigerator car provided with a hatchway, a plug for said hatchway, padding secured about said plug, an upstanding transversely curved cornerpiece secured in each corner of said hatchway and adapted to be engaged by said plug, and a closure for said hatchway adapted to protect said plug. 60

3. In a refrigerator car provided with a rectangular hatchway having walls converging downwardly, a corner shield of sheet metal secured in each corner of said hatchway, the corner portion of each shield being curved in cross-section, and a tapered plug adapted to be inserted in said hatchway, 70 said plug being rectangular in cross-section and padded on all four side edges. 75

4. In a refrigerator car provided with a hatchway having a tapered upper portion, a metallic strip curved in cross-section extending along each corner of said hatchway and provided with a flange at each end thereof for securing said strip in position and for forming a closed air space between said strip and the corner walls of said hatchway, and a tapered plug for said hatchway, said plug having padding on its peripheral edge for forming an air-tight joint between said plug and the walls and strips of said hatchway. 80

5. In a refrigerator car provided with a hatchway, a metallic corner piece, curved in cross-section, secured in each corner, the radius of said curve increasing downwardly toward the intermediate portion of said corner piece, and a plug having padding on its peripheral edge, for closing said hatchway. 85

In testimony whereof I affix my signature.

MATTHEW CARR.
